(57) CLAIM

The ornamental design for a combination shirt and garter, as shown and described.

DESCRIPTION

FIG. 1 is a front perspective view of a combination shirt and garter, showing my new design with a garter portion in an extended configuration;

FIG. 2 is a rear perspective view of FIG. 1;

FIG. 3 is a front elevational view of FIG. 1;

FIG. 4 is a rear elevational view of FIG. 1;

FIG. 5 is a left-side elevational view of FIG. 1;

FIG. 6 is a right-side elevational view of FIG. 1;

FIG. 7 is a top plan view of FIG. 1;

FIG. 8 is a bottom plan view of FIG. 1;

FIG. 9 is a rear elevational view thereof, illustrated with the garter portion in a rearward configuration;

FIG. 10 is a left-side elevational view of FIG. 9; and,

FIG. 11 is a perspective view thereof, illustrated with the garter portion in a lowered configuration.

The broken lines in the figures showing a person depict environmental matter that forms no part of the claimed design. The dot-dash broken lines in the figures depict a boundary of the claimed design, the broken line sleeves extending beyond the boundary forming no part of the claimed design. The remaining broken lines depict stitching, and do form part of the claimed design.

1 Claim, 9 Drawing Sheets
